UNITED STATES PATENT OFFICE.

RICHARD F. PREUSSER, OF WASHINGTON, DISTRICT OF COLUMBIA.

WHEEL-GUARD.

SPECIFICATION forming part of Letters Patent No. 652,863, dated July 3, 1900.

Application filed December 6, 1899. Serial No. 739,404. (No model.)

To all whom it may concern:

Be it known that I, RICHARD F. PREUSSER, a citizen of the United States, residing at Washington, in the District of Columbia, have 5 invented certain new and useful Improvements in Wheel-Guards; and I do hereby declare the following to be a full, clear, and exact description of the invention, such as will enable others skilled in the art to which it app- 10 pertains to make and use the same.

The object is to present a wheel-guard which in operation shall perform the functions usually confined to car-fenders—that is to say, a wheel-guard which normally will be 15 above the road-bed, but which in cases of emergency may with rapidity and ease be projected downward into such proximity to the road-bed as to pick up any object which may pass under the car, and thus be thoroughly 20 effective in saving life and limb.

The present invention is adapted particularly for use in connection with railway street-cars, such as usually employed on suburban routes, wherein a fender, such as is required 25 to be used within city limits, is generally dispensed with.

With the objects stated in view the invention is characterized, generally stated, in a wheel-guard, which may be of any ordinary 30 construction and supported in such manner as to be readily responsive to pressure, which will tend to rock the same to bring the guard into operative proximity to the road-bed, and automatically - operating means combined 35 with the guard whereby normally to hold it out of contact with the road-bed and after operation automatically to return it to its normal position above the road-bed.

The invention consists in the novel construction and combination of parts of a wheel-guard, as will be hereinafter fully described 40 and claimed.

In the accompanying drawings, forming a part of this specification, and in which like 45 letters of reference indicate corresponding parts, I have illustrated a form of embodiment of my invention, it being understood that other forms of embodiment may be employed without departing from the spirit of the same.

In the drawings, Figure 1 is a view in elevation, partly in section, displaying so much

of the lower portion of a street-car as is necessary to render clear an understanding of my invention and showing, further, the wheel-guard positioned thereon. Fig. 2 is a detail perspective view of the wheel-guard-actuating shaft. Fig. 3 is a similar view of the wheel-guard-actuating spring.

In Fig. 1, wherein the wheel-guard and its 60 actuating mechanism are shown, a part only of the guard is shown, as well as its actuating mechanism, it being understood that the parts are duplicated, so that a description of one of each of the parts will serve for the 65 remaining part. (Not shown.)

Referring to the drawings, A designates the wheel-guard, the same comprising two side arms a , the arms being connected together and rendered rigid by cross-bars a^2 , a^3 , 70 a^4 , these bars to be made either tubular or solid, as may be preferred. To the bars a^2 and a^4 are connected resilient metallic strips a^5 , constituting the scoop, it being understood, however, that, if preferred, in lieu 75 of the metallic strips ordinary rope or wire-netting may be employed. The cross-bar a^3 carries near each end adjacent to the side arms a a roller a^6 , which is adapted when the guard is depressed to contact with the road-bed or with the track-rollers, as usual, thus to keep the wheel-guard from contact with the road-bed, which might tend to cause its destruction. The cross-bar a^4 is journaled at 80 its ends in brackets a^7 , secured to suitable 85 hangers or the like a^8 , supported from the car-floor, the pivotal point of the side arms being below the center, whereby the bulk of the weight will be above the same, and the arms are curved in such manner as to throw 90 the greatest length of the arm back of the pivotal point, so that the arms will operate automatically to keep the guard out of contact with the road-bed.

Journaled in suitable hangers b , secured to 95 the under side of the car, is a rock-shaft B, the same being, by preference, rectangular in cross-section, as shown in Fig. 2, or it may be circular or of other form, and to this shaft are secured two upward and rearward curved 100 or bent arms b^2 , to which are pivoted one end of links b^3 , the other ends of which are pivotally connected with the side arms of the guard-frame A. Secured to this shaft B, pref-

erably near its center, is a plate b^4 , the free end of which is provided with a slot b^5 , in which works the lower end of a foot-lever C, the upper end of this lever projecting above the floor of the car adjacent to the dashboard and having a head c, by which it may be depressed. Carried by the foot-lever C above the plate b^4 are two friction-rollers c^2 , (indicated in dotted lines,) which bear upon the plate on each side of the slot, and below the plate is a stop-pin c^3 , which serves to hold the plate against separation from the foot-lever. The foot-lever is held normally elevated, as shown in Fig. 1, by a spring D, preferably 10 U-shaped, as shown in Fig. 3, and secured to the under side of the car-floor, the ends of the spring being provided with eyes d for this purpose, as shown in Fig. 3, while the loop of the spring passes around each side of and 15 bears against the under side of the plate b^4 . It will be seen from the arrangement of the parts that, owing to the upward stress of the spring D, the guard will at all times be held elevated above the road-bed; but should it be 20 desired to project the wheel-guard downward pressure upon the foot-lever C will through the arms b^2 and links b^3 project the guard downward into position to pick up any object which might pass under the car. Immediately 25 upon pressure being removed from the foot-lever C the guard will through the spring D automatically resume its normal position.

Having thus fully described my invention, what I claim as new, and desire to secure by Letters Patent of the United States, is—

35

1. The combination with a wheel-guard pivotally supported in such manner as to throw the weight of the guard to the rear of its pivotal points, of a rock-shaft carrying rearward-projecting arms and a forward-projecting 40 plate, links connecting the arms and the wheel-guard, and a foot-lever in engagement with the plate to project the guard into operative proximity to the road-bed, substantially as described.

45

2. The combination with a wheel-guard pivotally supported in such manner as to throw the weight of the guard to the rear of its pivotal points, of a rock-shaft carrying rearward-projecting arms and a forward-projecting 45 plate, links connecting the arms and the wheel-guard, a foot-lever in engagement with the plate to project the guard into operative proximity to the road-bed, and a spring for exerting upward pressure on the plate, whereby, normally, to keep the guard out of contact with the road-bed, substantially as described.

50

In testimony whereof I affix my signature in the presence of two subscribing witnesses.

60 RICHARD F. PREUSSER.
